UNITED STATES PATENT OFFICE.

ROBERT L. PRAHAR, OF MASSAPEQUA, NEW YORK.

BAG-JAW FASTENER.

1,189,733.

Specification of Letters Patent.

Patented July 4, 1916.

Application filed March 3, 1916. Serial No. 81,806.

To all whom it may concern:

Be it known that I, ROBERT L. PRAHAR, a citizen of the United States, and resident of Massapequa, in the county of Nassau and State of New York, have invented certain new and useful Improvements in Bag-Jaw Fasteners, of which the following is a specification.

This invention relates to fasteners for hand-bags, satchels, pocketbooks and other like articles, having pivoted frames or jaws separated to permit access to be gained to the interior.

In the ordinary constructions, the jaws or frames are liable to accidentally spring open and permit the contents to be lost or surreptitiously removed, in case the bag is too full, the spring of the fastener is too weak, or the fastener becomes bent or worn. Various attempts have been made to prevent this accidental opening of the bag by providing auxiliary or supplemental fastening devices. Some of these are so expensive as to render them impractical, others are too difficult to operate, and others, which involve two separate and independent fasteners, do not materially add to the safety as each is independently liable to become disengaged.

In my improved construction, I provide a fastening device which may be similar in most respects to others now in use and in connection therewith, I provide an auxiliary fastener adapted to engage with the first mentioned fastener and positively hold the former in locking position. Preferably, the main fastener is pivoted and held in place by a spring as in the ordinary construction, while the second is pivoted about an outwardly extending, substantially horizontal pivot and has a handle pivoted thereto. The fastening devices are carried by separate frame members and the handle which is pivoted to the auxiliary fastener normally depends therefrom so as to act by gravity and prevent the auxiliary fastener from moving to inoperative position. The handle may also be swung out away from the frame and grasped in one hand while the main fastening member is grasped in the other hand to facilitate the opening of the bag. The auxiliary fastener must be positively rotated through a considerable arc before the main fastener can be released, and as gravity acting on the pivoted handle normally prevents it from swinging, it will be seen that the main fastener cannot be dis-

engaged by any pressure from the interior of the bag.

My invention may be incorporated in various different forms and therefore I do not desire to be limited to any specific details and arrangement of parts shown in the accompanying drawings. I desire these to be considered merely in an illustrative rather than in a limiting sense.

In these drawings, to which reference is to be had and in which similar reference numerals indicate corresponding parts in the several views, Figure 1 is a side elevation of a device embodying my invention; Fig. 2 is a central vertical section; Fig. 3 is a side elevation of a portion similar to Fig. 1, but showing the auxiliary fastener moved to unlocking or releasing position; Fig. 4 is a section similar to Fig. 2, but showing another form which my invention may assume; and Fig. 5 is a view similar to Fig. 1, but showing the construction of Fig. 4.

In the specific construction illustrated in Figs. 1, 2 and 3 there are employed two frame or jaw members 10 and 11 connected at their ends by pivots 12. Each is of substantially U-shape in cross section and may have any suitable means for holding the walls of the bag within the channels. The construction of the frames and their pivotal connections form no portion of my present invention.

On one of the frame members, for instance the member 11, I provide a pivoted fastening member which may be constructed and mounted in various ways. As illustrated, it includes a cup-shaped piece 13 with a tongue or loop 14 projecting through a slot in the top wall of the frame 11 and receiving a torsion spring 15 within the loop. The cup extends across the top walls of both frame members and when in operative position, as shown in Fig. 2, incloses, extends over, or engages with, a stud 16. To facilitate the swinging of this fastening member, the cup-shaped portion 13 may have a knob 17 rigidly connected thereto. This construction, so far as described in detail, involves no portion of my present invention but is substantially the same as that illustrated in the L. B. Prahar Patent No. 1,143,226, issued June 15, 1915. Although I have shown the cup-shaped member 13 engaging with an upwardly extending stud 16, it is evident that the cup, which is pivoted to the member 11, may interlock with the frame member 10, or

a part thereon, in any suitable manner to insure the holding together of the frame members when this main fastening device is in operative position. It may be readily disengaged by pressing the knob upwardly and toward the right from the position shown in Fig. 2 so that it will swing about an axis extending in the general direction of the length of the frame.

10 The cup member 13 of the main fastening device includes as an important feature of my improved construction an outwardly, or outwardly and upwardly, extending catch or projection 18. Mounted on the frame member 10 is a device for engaging with this catch or projection so as normally to positively prevent the upward and backward swinging of the main fastening device. In the specific form illustrated in Figs. 1, 2 and 15 3, this auxiliary lock or fastener includes a stud or pivot 19 riveted or otherwise rigidly secured to the side wall of the frame member 10 and projecting outwardly substantially at right angles to the general plane of 20 the frame. Mounted to turn on this pivot is a member 20 having a tongue or hook portion 21 which may extend over and engage with the upper side of the tongue or projection 18. As a simple and inexpensive 25 method of forming this member 20, it may be stamped from sheet metal so that the body portion thereof is substantially hemispherical while the tongue 21 projects from one edge thereof. With the members in the 30 position indicated in Figs. 1 and 2, the main fastening member cannot be disengaged. For normally holding it in this position, facilitating its movement to inoperative or 35 unlocking position, and for facilitating the separation of the jaws or frames, I pivotally 40 connect a handle member 22 to the catch or fastener member 20. As shown the handle has oppositely disposed, inwardly directed 45 pivot portions 23 which extend into opposite walls of the member 20 so that the handle, when in normal position, hangs down substantially vertically. The action 50 of gravity on this handle tends to prevent the fastening member 20 from rotating about the pivot 19 and therefore holds the parts 18 and 21 in coöperating relationship.

The handle may be employed to turn the member 20 about the pivot 19 to such an extent that the tongue or projection 21 will no 55 longer lie above the part 18 as is shown in Fig. 3. If desired, the handle may also be swung about the pivots 23 so as to extend outwardly from the frame, and either before or after being swung to this position, may 60 be employed for rotating the member 20. When the handle 22 is grasped in one hand and the knob 17 in the other, the member 20 may first be rotated and then the knob swung upwardly and the frames separated. The 65 handle thus serves as a weight to act by

gravity and hold the auxiliary fastener in place; as a means for rotating the member 20 to inoperative position; and as means for pulling the frame members apart. As the handle 22 when released swings back to its 70 depending position and re-locks the main fastener, it is evident that the bag cannot very well be opened by the use of one hand alone and thus it is more difficult for a person to open the bag to remove its contents without attracting the attention of the owner. In case the member 20 be rotated through a half revolution so that the part 21 extends downwardly instead of upwardly, the handle 22 will engage with the top of the 75 part 21 and will project outwardly at an angle to the plane of the frame, and the fact that it does not lie down smooth against the side of the frame, may be noticed at once by the owner, and thus it serves as a warning that 80 the auxiliary lock is not in proper position.

A further embodiment of my invention is illustrated in Figs. 4 and 5. Here, the principle of operating is the same although the details of construction are somewhat different. The main fastening member is made of a rectangular cup 13^a of sufficient height to avoid the necessity for a separate knob or handle thereon. Instead of having one edge provided with a lip or projection as in Figs. 90 1, 2 and 3, a portion of the side wall of the cup-shaped casing is struck outwardly to form a ledge or projection 18^a, the upper surface of which may be, and preferably is, curved in an arc, the center of which is the 95 axis of the pivot 19^a. This pivot may be formed integral with a fastening member 20^a and may rotate in an aperture in the side wall of the frame 10. The member 20^a may have a tongue or extension 21^a which extends 100 upwardly and terminates in a flange lying above the ledge or shoulder 18^a. A further 105 description of the construction and operation appears to be unnecessary.

Having thus described my invention, what 110 I claim as new and desire to secure by Letters Patent is:

1. In combination, a pair of frame members, a fastener pivoted to one member and adapted to engage with the other member to 115 hold said members together, and an auxiliary fastener pivoted to the side of the other frame member and normally preventing the disengagement of the first mentioned fastener, said second mentioned fastener having depending gravity operating means for normally retaining it in operative position.

2. The combination with a pair of frames, of a member carried by one frame extending across the upper surface and projecting beyond the other frame, and a fastener pivoted to the side of the second mentioned frame and rotatable about an outwardly extending, substantially horizontal pivot, said fastener having means for engaging with said mem- 125 130 135

ber to prevent movement of the latter in respect to the second mentioned frame, and also having depending gravity operated means for normally preventing rotation of 5 said fastener.

3. The combination with a pair of frames, of a member carried by one frame extending across the upper surface and projecting beyond the other frame, and a fastener 10 pivoted to the side of the second mentioned frame and rotatable about an outwardly extending, substantially horizontal pivot, said fastener having means for engaging with said member to prevent movement of the 15 latter in respect to the second mentioned frame and having a handle pivoted thereto and depending therefrom to normally prevent accidental rotation of said fastener.

4. The combination with a pair of frames, 20 of a fastener pivoted to one frame to move about an axis extending in the general direction of the frame and adapted to engage with the other frame to hold the frames together, and a second fastener carried by the 25 other frame and pivoted to move about an

axis substantially at right angles to the plane of the frame and adapted to engage with the first mentioned fastener to normally prevent movement of the latter.

5. The combination with a pair of frames, 30 of a fastener carried by one frame and adapted to engage with the other to hold the frames together, an outwardly extending pivot carried by the other frame on the outer side thereof, a member mounted on said 35 pivot and having a projecting portion adapted to engage with said fastener, and a handle pivoted to said member and normally depending therefrom to act by gravity and prevent accidental rotation of said member and serving as means for the positive rotation of said member and the disengagement of said projecting portion from said fastener.

Signed at Brooklyn in the county of 45 Kings and State of New York, this 1st day of March, A. D. 1916.
